UNITED STATES PATENT OFFICE.

ANGELO PITTONI, OF LYNBROOK, NEW YORK, ASSIGNOR TO ROME METALLIC BED-STEAD COMPANY, A CORPORATION OF NEW YORK.

FOLDING BED.

Application filed February 14, 1925. Serial No. 9,090.

The present invention relates to folding beds, and in particular I aim to produce a folding bed embodying deep coil springs on both halves. Broadly speaking, my invention consists in making the spring frame in two halves, one-half being intended to move laterally without being turned upside down, and the other half being mounted on a movable pivot so that it can be turned over without having the deep springs and mattress hit the floor.

In the accompanying drawings which show illustrative examples of a bed embodying my invention, Fig. 1 is a perspective view of one form of bed partly open, with the springs removed; Fig. 2 is a detail view showing the relationship of the relatively slideable parts of the main frame and the auxiliary support frame; Fig. 3 is an end view of a bed in closed position; Fig. 4 is a similar view showing the bed partly open; Fig. 5 is a view showing the bed fully open; Fig. 6 is a detail plan view of the hinges between the two pivoted spring frames; Fig. 7 is an end view of the parts shown in Fig. 6, and Fig. 8 is a view of the same hinges in an intermediate position. Of these, Fig. 9 is an end view of the bed in closed position; Fig. 10 is a detailed plan view of one end of the bed; Fig. 11 shows the bed just after the opening movement has begun; Fig. 12 shows the fully opened position, and Fig. 13 illustrates the initial closing movement.

The main frame members 2 may be made in any desired manner. In the example illustrated they are shown as made of bent hollow metal. If desired, ornamental ends as 3 (see Fig. 5) may be attached to the ends 2. Each main frame member 2 has a transverse bar 4 approximately in the middle and a slide rod 5 above the bar 4. It is to be noted, as shown in Fig. 1, that the bar 4 is L-shaped in cross section except where it is bent for attachment to a main frame member 2. An L-shaped arm 6 is pivoted to a bracket 6^a which is attached to each bar 4 near one of its ends. Pivoted to the long arm of lever 6 is a rectangular spring frame 7 intended to carry a spring 8 made up of relatively deep coils 9. (In Figs. 3 and 5 the position of the spring is indicated by broken lines.) At each end of the frame 7 near one side thereof is a roller 10 which is adapted to move on the flat face of bar 4.

A stop 11 is mounted on the upper face of the bar 4 to limit the movement of the roller 10. A spring 12 connects the short arm of lever 6 with one leg of main frame 2.

A second rectangular spring frame 14 is hinged to one side of frame 7 and is adapted to carry a wire spring 15 similar to the spring 8. The other edge of the frame 14 is pivoted to a pair of lugs 16 attached to two auxiliary supporting members 17. Frame members 17 are provided at the ends which form legs, with rollers or casters 18 and at their other ends are provided with brackets 19 which slide on rods 5; in other words, the members 17 can be moved laterally in relation to the members 2 without any relative tilting movement between the two.

The longitudinal connections here illustrated as positioned between the members 2, comprise main tie rods 20 and brace brackets 21.

As shown in Figs. 6, 7 and 8, the hinges between frames 7 and 14 are so arranged that these two frame members can lie either one above the other with the two frames in contact, or side by side. It is also to be noted that the frame 7 has two projecting arms 22 which overlap the ends of frame 14 and that these arms are at the opposite side of frame 7 from rollers 10. Frame 7 is made of such a width that when the bed is open and rollers 10 are against stops 11, the arms 22 will rest on two of the brace brackets 21 but the longitudinal bars of frame 7 will be intermediate the planes of brace brackets 21 so that the edge of frame 14 which is adjacent frame 7, will likewise rest on two brace brackets 21. When the parts are in this position, frame 7 will be in a state of stable equilibrium, as one edge will be supported by the arms 22, while the other side will be supported by rollers 10. To move frame 7, the hinged joint between frames 7 and 14 must be lifted. In order that this may be readily accomplished, frame 14 is provided with two loops or handles 24.

When the bed is closed, frame 14 will lie immediately above frame 7 and will be supported by it, with auxiliary frame members 17 lifted slightly off the floor. The hinge at the back edge will again be supported by arms 22 which will rest on the back pair of brace brackets 21.

In the operation of the device, if we consider that the bed is closed as shown in Fig.

3, one wishing to open it grasps handles 24 and pulls them up and forward. Frame 7 will rock on pivot 10 which will lift the long end of lever 6, and this lift will be assisted by the action of spring 12. Since lever 6 has a fixed pivot connected with frame member 2, roller 10 will move along bar 4 until frame 7 will be in a vertical position when the roller 10 is immediately below the pivot at the free end of the long arm of lever 6. While frame 7 is being moved into this position, members 17 will be pushed forward away from members 2 by the thrust exerted through frames 14. As the movement of frame 7 is continued, roller 10 will move out from under lever 6, and passing through the position shown in Fig. 4, will move against stop 11, when frame 7 will lie in its open position; at the same time frame members 17 will have been moved laterally to their extreme open position as shown in Fig. 5. To close the bed, the handles 24 are pulled up, and frame 7 is rocked until it is turned back into the position shown in Fig. 3, which will cause frame members 17 to slide back into closed position.

It may be noted that by providing the movable pivot 10, I am able to so arrange the parts that there is substantial clearance at all times between the spring 8 carried by frame 7 and the floor or side members of the bed. This permits me to utilize a spring with coils of the same depth as are used in ordinary stationary beds. Also by this arrangement I can provide an ornamental longitudinal member 25 connecting two frame members 17, which when the bed is closed, will cover up the front edge of spring 8. If desired, the ornamental ends which are shown in Fig. 5 as attached to frame members 2 may be attached to the frame members 17 as shown at one end of the bed in Fig. 1, in which event they will slide back and forth with these frame members.

It is to be understood that the foregoing examples are given by way of illustration only and that the same may be modified in

many details without departing from the spirit of my invention.

What I claim is:

1. A main support frame, a second support frame movable telescopically relative thereto, a spring frame one edge of which is pivotally supported by said second support frame, a second spring frame hinged to said first spring frame, and means for supporting said second spring frame in said main support frame comprising a pivot member at each end of said second spring frame at a substantial distance from the longitudinal median thereof, and a track on said main frame along which said pivot members are adapted to move laterally of said main frame.

2. A device as characterized in claim 1, wherein there are provided, adjacent the mechanism for hinging together the two spring frames, members adapted to contact with portions of the main support frame to maintain said second spring frame in equilibrium when said spring frame is horizontal.

3. A device as characterized in claim 1, comprising a pair of arms pivoted to the main support frame near one side thereof, and pivoted to said second spring frame at the ends of the longitudinal median thereof.

4. A device as characterized in claim 1, comprising a pair of arms pivoted to the main support frame near one side thereof, and pivoted to said second spring frame at the ends of the longitudinal median thereof, and means connecting said arms to the main frame tending to raise said arms.

5. In a bed of the class described, a main frame and a supplemental main frame movable telescopically with relation to each other, a reversible spring frame mounted within said main frame to rotate upon a slideable pivot and another spring frame hinged to said reversible spring frame and pivoted to said supplemental main frame.

ANGELO PITTONI.
